DRILLING APPARATUS

Harland W. Cardwell, Wichita, Kans., assignor to
Cardwell Manufacturing Company, Inc., a cor-
poration of Kansas

Application September 16, 1937, Serial No. 164,223

3 Claims. (Cl. 74—41)

This invention relates to improvements in drilling apparatus, and is more particularly concerned with reciprocating beams for well drilling or potential pumping and suitable multiple speed drive connections therefor.

It is an object of the present invention to provide a novel beam mounting whereby the beam may be moved bodily transversely of the work so as to clear the drilling tools as distinguished from the swivel movement of the beam heretofore employed. More specifically, the invention provides a transverse header of substantial length and a bearing slidably mounted upon the header and pivotally supporting the beam. The bearing is connected with one end of an elongated screw threaded bar and means is provided for cooperating with said bar to move the bearing and beam longitudinally of the header a substantial and sufficient distance for the working end of the beam to clear the well hole when desired. The beam may thus be moved along the header lengthwise of the header instead of being rotatably fulcrumed upon one end of a Samson post as is customary. Advantages of the foregoing construction are found in the fact that a unit employing the features of the present invention is compact and sturdy as compared with prior beam drilling units and requires but a minimum area for operation.

A further object of the invention contemplates the provision of means whereby the driving mechanism for the beam will not interfere with movement of the beam relative thereto, and whereby it is unnecessary to disconnect the driving means from the beam when it is desired to move the beam out of or into operative alignment with the well for drilling or pumping. This object is obtained by providing self-aligning or universal bearings at the points of connection of the pitman with the beam and driving crank or other rotatable member.

Another object is to provide a drilling and pumping beam and operating means therefor which is attachable as a unit to any conventional single or plural drum draw works but particularly adapted for use with devices such as described in Guier and Brown Patent No. 2,028,701, having a variable speed transmission so as to effect a beam drilling or well pumping operation.

A further object and advantage is to provide a beam drilling attachment which is so associated with the draw works that the draw works may be operated independently of the beam attachment for rotary drilling or the like without necessarily removing the beam attachment.

A further object is to provide novel means whereby the beam attachment may be readily mounted upon and associated with the draw works.

Other objects and advantages will be apparent

from the following detailed description and the accompanying drawings wherein a preferred embodiment of the features of the invention is selected for exemplification.

In the drawings:

Figure 1 is a side elevation of a drilling unit equipped with novel features of the present invention;

Figure 2 is a fragmentary view taken on line 2—2 of Figure 1 illustrating the header with the beam and beam bearing mounted thereon;

Figure 3 is an enlarged fragmentary view at the rear of the unit of Fig. 1 illustrating particularly the pitman and crank pin connection for operating the beam;

Figure 4 is a view similar to Figure 3 illustrating the connection between the beam and pitman;

Figure 5 is a detailed section taken along line 5—5 of Figure 1;

Figure 6 is a transverse section of the connection shown in Figure 5 and taken along line 6—6 thereof;

Figure 7 is a detailed section taken along line 7—7 of Figure 1; and

Figure 8 is a transverse section of the connection shown in Figure 7 taken along line 8—8 thereof.

Referring more particularly to the drawings wherein like numerals are used to designate like parts, the unit illustrated is provided with skid supports 10 which serve as a base for the conventional draw works drums 12 and 14 operated in any suitable manner by prime mover 16. While a plurality of drums are illustrated, the elements thus far described form no part of the present invention and any number or arrangement of drums may be used with any suitable base.

The power unit 16 very desirably includes a variable speed transmission such as described in Guier and Brown Patent No. 2,028,701 so that the speed of the beam attachment which is powered from this source may be readily controlled.

The beam drilling and pumping attachment is supported upon a suitable base or skids indicated at 11 upon the forward end of which the draw works unit is mounted as clearly shown in Fig. 1.

Mounted upon the base 11 and disposed rearwardly of the draw works is a shaft 17 carrying a sprocket wheel 18 and a crank 26 carrying a crank pin 22 and driven by sprocket chain 20 which in turn is operated by sprocket wheel 21 at the power output end of a variable speed transmission which transmission is attached to prime mover 16 of the draw works.

A pitman 24 is connected to crank pin 22 by means of the crank 26 which is fixed at one end to the shaft 17 and at its opposite end to the pit-

60

man 24 by means of a self-aligning bearing 28, as best shown in Figure 3. Pitman 24 at its opposite end is forked as at 30 to receive an end of beam 32 and is operatively connected to beam 32 by means of a self-aligning bearing 34. It will be apparent that self-aligning bearings 28 and 34 permit lateral movement of the beam 32 with respect to pitman 24 and crank pin 22 to the extent that the beam may be readily moved into and out of its normal vertical plane without disconnecting therefrom its operating pitman or without disconnecting the pitman from the crank pin.

Header board 36 is disposed transversely of the unit and supported by upstanding jack posts 38 and may, if desired, be tied down or further secured by means of suitable cables or the like 40. Header 36 may be of substantial I-shape in cross-section and, in the preferred embodiment 20 of the invention, is provided at its upper edge with laterally extending flanges 42 which receive the complementary inturned flanges 44 of a support 46 for beam bearing 48. At its forward end, beam 32 is provided with a conventional temper 25 screw 50 for supporting any suitable drilling or pumping means (not illustrated) and is journaled intermediate its ends to trunnion or bearing 48 and its support 46 for rocking or reciprocating motion over the well or hole.

30 The purpose of mounting beam 32 in the manner illustrated and above described is to permit lateral movement of the beam into and out of its normal alignment with the hole to clear the tools or pumping rods or return them to operative 35 position. It will be apparent that beam 32 and its bearing 48 may be moved in their entirety laterally and transversely of the header 36 and to thus move the beam and its bearing, a screw 52 may be provided which is fixed at one end to bearing support 46 as at 54 and threadedly received at its opposite end by sheave 56 fixed on the header board which sheave may in turn be manually operated by sheave chain 58.

Figures 5 and 6 illustrate in detail the self-aligning bearing indicated generally at 34 for connecting beam 32 to the pitman 24, only the fork end 30 of which is shown, while Figures 7 and 8 illustrate in detail the self-aligning bearing indicated generally as 28 for connecting pitman 24 to the crank pin, and further showing tensioning means 29 which it is desirable to employ for cooperation with bearing 28.

The operation of the foregoing construction is believed readily apparent from the illustration and description thereof, and the distance to which the beam may be transversely shifted with respect to header 36 without disconnecting the beam driving means is determined by the length of the header as well as the length of the screw 52 and the pitman and crank pin arrangement including the self-aligning bearings 28 and 34 above described. Moving beam 32 transversely of header 36, as in the present invention, provides an important advantage over a fixed pivotal 60 connection sometimes employed between the beam and the header in that the pitman end of the beam moves only a fraction of the distance that the tool bearing end of the beam is moved and it is thus possible to employ a very sturdy 65 swivel connection for the pitman, whereas pivotal movement of the beam would result in a lateral shift of both ends of the beam an equal distance, and a swivel pitman connection employed

therewith, because of its necessary flexibility, would be incapable of satisfactory operation under the severe strains to which it would be ordinarily subjected.

It is understood that the specific construction 5 herein illustrated and described is exemplary only of the principles of the invention which are limited only by the scope of the following claims.

Having described my invention, I claim:

1. An attachment for use in well drilling and 10 pumping comprising, a header of substantial length; a beam disposed transversely of said header; means pivotally and slidably supporting said beam on said header, said means including a bearing member secured to the lower side of 15 said beam, a supporting member resting on said header having spaced arms, and means pivotally connecting said bearing member to said spaced arms; and means for moving said beam and slidably supporting member along the header in a 20 direction lengthwise of said header, said means comprising, an elongated screw bar having one end thereof extending through one of said arms and connected with said slidably supporting member and a rotatable member on the opposite 25 end of said screw bar cooperable with said screw bar for moving said beam from a position medially of said header to a remote position adjacent one end of said header.

2. An attachment for use with a draw works 30 comprising, a header of substantial length adapted to be secured to a draw works; a rockable beam disposed transversely of said header; means rockably and slidably supporting said beam on said header, said means including a bearing member secured to the lower side of said beam, a supporting member resting on said header having spaced arms, and means pivotally connecting said bearing member to said spaced arms; and means for moving said beam and slidably supporting means along the header in a direction 35 lengthwise of said header, said means comprising, an elongated screw bar having one end thereof extending through one of said arms and connected with said slidably supporting means, a 40 journal for the opposite end of said screw bar carried by said header and a rotatable wheel member on said screw adjacent said journal operable to cause movement of said beam bodily from one position to another along said header. 45

3. Apparatus for use in drilling and pumping wells comprising, a base, uprights on two opposite sides of said base, a header supported by said uprights; a rockable beam disposed transversely of said header; means rockably and slidably supporting said beam on said header; a screw bar for moving said means; a threaded journal mounted on said header, one end of said screw bar being connected to said means with the threaded portion of said screw bar extending through said journal whereby upon rotation of said screw bar said beam will be shifted longitudinally of said header; and driving means for rocking said beam on said slidably support including a rotary member, a pitman, and 60 a self-aligning bearing connecting the opposite ends of said pitman to said beam and said rotary member, respectively, whereby said beam may be bodily moved along the header lengthwise of said header without requiring disconnection 65 of said pitman from either said beam or rotary driving member.

HARLAND W. CARDWELL.
